Specification for Design.

Patented Apr. 14, 1914.

Application filed February 2, 1914. Serial No. 816,109. Term of patent 7 years.

To all whom it may concern:

Be it known that I, WILLIAM O'SHEA, a citizen of the United States, residing at Kansas City, in the county of Jackson and State of Missouri, (whose post-office address is Hunter avenue and Broadway street, Kansas City, Missouri,) have invented a new, original, and ornamental Design for Crucifixes, of which the following is a specification, reference being had to the accompanying drawing, forming part thereof.

The figure is a front elevation of a crucifix, showing my design.

I claim:

The ornamental design for a crucifix, as shown.

WILLIAM O'SHEA.
